Letter Patent and drawing part of the same

Dear Sirs:

I wish to inform you that I am a member of the Philadelphia County of Philadelphia Office of Pennsylvania have invented or produced a new and original design for a tobacco pipe, and I hereby declare the accompanying drawing with the following explanation of the same to form a full, clear and exact description of the said design.

In the accompanying drawing the figure representing tobacco pipe A is the stem of the pipe, the lower tapering end of which is inserted in a socket in the upper end of a hollow handle or bowl. The latter being formed to represent a human arm and hand.

There is a socket turned in the handle at the middle end of the stem A, & it is upon a hollow projection at the underside of the bowl.

Claim.

The design for a tobacco pipe, substantially as shown and set forth in the accompanying drawing.

Witnessed, & I have signed my name to this specification
for me, the presence of two subscribing witnesses.

Witnesses:

John Whiteman
